CLAIM

The ornamental design for a seed reservoir bottle for a wild bird feeder, as shown and described.

DESCRIPTION

FIG. 1 is an exemplary perspective view of the seed reservoir bottle for a wild bird feeder showing our new design; FIG. 2 is a perspective view of the seed reservoir bottle for a wild bird feeder;

FIG. 3 is a right side perspective view of the seed reservoir bottle for a wild bird feeder, a corresponding opposite side perspective view being a substantial mirror image thereof; FIG. 4 is a front elevation view thereof; FIG. 5 is a side elevation view thereof; FIG. 6 is a rear elevation view thereof; FIG. 7 is a top plan view thereof; and, FIG. 8 is a bottom plan view thereof.

The broken line elements on the seed reservoir bottle are depicted for illustrative purposes only and form no part of the claimed design. The broken line showing of upper and lower bands of surface finish on the central body of the seed reservoir bottle, the lid and wire hanger on top of the seed reservoir bottle, and the feeding port assembly at the bottom of the seed reservoir bottle in FIG. 1 illustratively depicts
